(57) **CLAIM**

The ornamental design for an electrical connector, as shown and described.

DESCRIPTION

FIG. 1 is a front, top and left-side perspective view of an electrical connector showing our new design;

FIG. 2 is a front, bottom and right-side perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof;

FIG. 9 is an enlarged view of the area 9 indicated by the double dot-dash broken lines in FIG. 7;

FIG. 10 is an enlarged cross-sectional view taken in the direction of line 10-10 in FIG. 8; and,

FIG. 11 is another front, top, and left-side perspective view thereof shown in environment.

The evenly-spaced broken lines depict environment in the additional broken line structure shown in the FIG. 11 view and depict portions of the electrical connector, in the FIG. 1-11 views, that form no part of the claimed design. Also, the evenly-spaced broken lines in the FIG. 10 view depict the surfaces at the cut marks and form no part of the claimed design. The single dot-dash broken lines define the boundary of the claimed design and form no part of the claimed design. The rectangle indicated by the double dot-dash broken lines shown in FIG. 7 illustrates the boundary of enlarged area of the design. The "9" indicia and splined curve indicated by the double dot-dash broken lines in FIG. 7 identify the enlarged area. None of the double dot-dash broken lines form any part of the claimed design.

1 Claim, 9 Drawing Sheets
